UNITED STATES PATENT OFFICE.

ALBERT H. OVERMAN, OF HARTFORD, CONNECTICUT, ASSIGNOR TO THE
OVERMAN WHEEL COMPANY, OF SAME PLACE.

VELOCIPED.

SPECIFICATION forming part of Letters Patent No. 257,512, dated May 9, 1882.

Application filed February 1, 1882. (No model.)

To all whom it may concern:

Be it known that I, ALBERT H. OVERMAN, of Hartford, in the county of Hartford and State of Connecticut, have invented certain new and useful Improvements in Tricycles; and I do hereby declare the following to be a full, clear, and exact description of the invention, such as will enable others skilled in the art to which it pertains to make and use the same.

My invention relates to an improvement in tricycles, the object being to provide a tricycle of such construction that it shall be light and durable in its construction and adapted to be operated by a slight expenditure of power.

My invention consists in certain features of construction and combinations of parts, as will hereinafter be described, and pointed out in the claims.

20 The drawing represents a vertical longitudinal section of a tricycle constructed in accordance with my invention.

A³ represents one of the driving-wheels, which may be of any preferred form of construction. The driving-wheels are mounted on spindles a³, the inner ends of which are each supported by a hanger, B³. Upon each spindle a³ is loosely mounted a driving-disk, C³, which is constructed as shown and described in Letters Patent No. 242,212, whereby when it is rotated in one direction it will engage with and rotate the driving-wheel, and when turned in the opposite direction it will be disengaged from the driving-wheel.

25 D³ represents one of the depending side pieces of the frame, the lower end of which is bent, as at b³, from which point it extends forward in the form of a bow, as at c³. To the central portion of the bow c³ is secured the 30 curved piece d³, having the yoke E³ of the guide-wheel F³ swiveled thereto. The bow

35 portion c³ of the frame is provided with a cross-bar, a⁴, on which is mounted a brake, G³, consisting of an arm, e³, having a flat shoe, f³, attached to its lower end, and an arm, g³, which, being pressed downwardly by the foot of the rider, forces the shoe f³ in contact with the ground and arrests the speed of the vehicle. The brake is raised by means of a spring, h³.

40 Upon each of the sidepieces, D³, of the frame

is placed a sleeve, H³, to which is journaled the front pedal, I³, the latter having an end of a metal strap attached thereto, the other end being secured within the grooved periphery of the driving-disk. To the side of the driving-disk is attached one end of a coiled spring, K³, the opposite end being secured to the spindle or to the frame. By depressing the foot-pedal the driving-wheels are rotated forwardly, while pressure being relieved from the pedal the driving-disks are rotated in the opposite direction by the coiled spring K³.

A steering-handle is mounted in a support, M³, attached to the frame N³, which extends transversely between the wheels in rear of the inner ends of the spindles, thereby insuring a free and unobstructed space between the inner ends of the spindles for the legs of the operator. The guide-wheel is actuated by the handle L³ and rod O³ through the medium of an eccentric or rack bar, as desired.

To the central portion of the transverse frame-piece N³ is secured the standard P³ of the vertically-adjustable seat Q³. Also, to this frame is fastened the upper end of the safety-prop R³, which extends downwardly at any desired angle, the lower end thereof being provided with a roller, i³; or the roller may be dispensed with. This safety-prop effectually prevents the tricycle from tipping over backward.

The guide-wheel may be located centrally with respect to the driving-wheels, or at one side, as may be desired. By this construction of tricycle the guide-wheel is located in front 85 instead of in rear of the driving-wheels, as illustrated in Patent No. 242,212, while the driving-disks are retained and a free and unobstructed space provided between the disks and inner ends of the spindles to allow of the movement of the legs of the rider.

It is evident that many slight changes in the construction and relative arrangement of parts might be resorted to without involving a departure from the spirit of my invention, 95 and hence I would have it understood that I do not restrict myself to the exact construction and arrangement of parts shown and described; but,

Having fully described my invention, what 100

I claim as new, and desire to secure by Letters Patent, is—

1. In a tricycle, the combination, with the driving-wheels mounted on separate spindles, and driving-disks mounted on the spindles and engaging the hubs of the driving-wheels, of the main supporting-frame extending downwardly in front of the driving-wheel spindles and then forwardly, and supporting the guide-wheel, and foot-pedals pivoted to brackets sleeved on the vertical portions of the side frame-pieces, and straps or bands connecting the foot-pedals and driving-disks, substantially as set forth.
- 15 2. In a tricycle, the combination, with the

driving-wheels mounted on separate spindles, driving-disks mounted on said spindles, and foot-pedals for actuating the driving-disks, of a cross-bar located in rear of the spindles and supporting a seat, and side frame-pieces 20 extending downwardly in front of the spindles and forwardly, and supporting the guide-wheel, substantially as set forth.

In testimony whereof I have signed this specification in the presence of two subscribers.

ALBERT H. OVERMAN.
